ELECTRICALLY FIRED ROCKET PROJECTILE

Filed Sept. 22, 1943

UNITED STATES PATENT OFFICE

2,466,752

ELECTRICALLY FIRED ROCKET PROJECTILE

Edward G. Uhl, Elizabeth, N. J., and Leslie A. Skinner, Washington, D. C., assignors to the United States of America as represented by the Secretary of War

Application September 22, 1943, Serial No. 503,410

4 Claims. (Cl. 102—49)

(Granted under the act of March 3, 1883, as amended April 30, 1928; 370 O. G. 757)

1

The invention described herein may be manufactured and used by or for the Government for governmental purposes without the payment to us of any royalty thereon.

This invention relates to a rocket projectile, particularly to an electrically fired rocket projectile.

It is an object of this invention to provide a rocket projectile having a propelling charge ignited by electrical means.

A further object of this invention is to provide an improved supporting arrangement of the propellant charge within the rocket projectile.

The specific nature of the invention as well as other objects and advantages thereof will clearly appear from a description of a preferred embodiment as shown in the accompanying drawings in which:

Fig. 1 is a side elevational view shown partly in longitudinal section of the electrically fired rocket projectile.

Fig. 2 is an enlarged perspective fragmentary view of the head of the projectile showing the front electrical contact ring.

Fig. 3 is a side elevational view of the rocket propelling charge partly broken away to show the manner of mounting an electrically fired squib.

Fig. 4 is a left end view of Fig. 3.

Fig. 5 shows an alternate construction of the electrically fired squib.

Fig. 6 is a top elevational view of the propelling charge retaining ring.

There is shown in assembled relation in Fig. 1 a rocket projectile 1 embodying this invention. The rocket projectile 1 comprises a head 2 containing the explosive charge, a tubular body portion 3 and a nozzle 4. The head 2 of rocket projectile 1 is provided with a conical ogive shaped end cap 5 welded or otherwise secured to the head 2 and a guiding land 24. An integral shank portion 6 is provided on the rear end of head 2 which is inserted within one end of tube 3. A propellant charge containing tube 3 is secured to shank portion 6 in any suitable manner such as by the screws 7 spaced about the periphery of tube 3. An annular nozzle member 4 is secured to the extreme rear end of tube 3 as by threads 8. Nozzle member 4 defines an orifice 9 which opens to the rear of rocket projectile 1. Orifice 9 is of conventional Venturi construction as shown in Fig. 1 such as to form a gas blast from the gases developed by the propellant charge, the reaction force of which provides the propelling force for the projectile. A plurality of fins 10 are mounted about the periphery of nozzle

2

4. The fins 10 serve to stabilize the projectile in flight.

A propulsion charge 14 (Figs. 1, 3 and 4) comprising a bundle of powder sticks 15 securely fastened together as by several loops of wire or thread 16 is inserted within tube 3. The bundle 15 is formed with a hollow central portion 29. A propellant charge retaining ring 11 (Figs. 1 and 6) is mounted on a pair of crossed rod supports 12. The rod supports 12 are placed between the threaded end of tube 3 and a shoulder 13 provided on the inside of nozzle member 4. When nozzle member 4 is screwed tightly against the rods 12, ring 11 will be securely supported and hence will retain propulsion charge 14 within tube 3.

An electrically fired squib 17 is provided to ignite the propulsion charge 14. Two insulated electrical conducting wires 18 and 19 connect with squib 17 and are led thru the center of charge 14 and out thru orifice 9.

The wires 18 and 19 secure squib 17 against the left end of charge 14 as viewed in Figs. 1 and 3. The wire 19 is laid along the outside of nozzle 4 and tube 3 to the head 2 of rocket projectile 1. The wire 19 may be secured in place by a narrow strip of adhesive tape 20 placed over wire 19. The wire 19 terminates approximately in the center of head 2 and at this point is soldered to a thin strip of metal 21 of high electrical conductivity. The strip 21 extends forwardly of head 2 and connects with a contact ring 22 of the same metal. The strip 21 is laid adjacent head 2 within a tube 25 of suitable insulating material shown in exaggerated size in Fig. 2.

The contact ring 22 is mounted snugly on the conical end cap 5 of head 2. An intermediate layer of insulation 28 insulates ring 22 from head 2. The other wire 18 is soldered to the bottom of a V-shaped contact notch 26 provided in one of fins 10.

A cartridge type electrical squib 27 as shown in Fig. 5 may alternately be employed to ignite powder charge 14. Such a squib comprises a headed metallic case 27 which is inserted in the left end of the hollow portion 29 of the bundle of powder sticks 15 as shown in Fig. 5. The interior construction of squib 27 is conventional and igniting wires 18 and 19 project out of case 27.

The rocket projectile 1 is readily launched by ignition of propulsion charge 14 by application of an electrical voltage between contact ring 22 and contact notch 26. Due to the location of squib 17 within the hollow portion of charge 14 all of the interior surfaces of powder sticks 15 are ignited, thereby producing very efficient combus-

tion of the propulsion charge. The gases generated are formed into a blast by orifice 9 and the reaction forces of the gas blast propel the rocket projectile 1 in its flight.

It will be noted that the open structure of the retaining ring 11 does not appreciably interfere with the gases generated and yet retains the propulsion charge 14 within tube 3 until completely burned.

Thus the structure of this invention permits rapid assemblage of the propellant charge within a rocket projectile and provides positive ignition and efficient combustion of the charge.

We claim:

1. In a rocket projectile, a hollow body portion, a self-contained propulsion charge insertable in said body portion, means for retaining said charge within said body portion, an electrical squib mounted adjacent said charge, a pair of electrical contact surfaces on the periphery of the rocket projectile, at least one of said contact surfaces being insulated with respect to the rocket projectile, and electrical conductors connecting each of said contact surfaces to said electrical squib.

2. In a rocket projectile, a hollow body portion, a self-contained propulsion charge insertable in said body portion, a hollow finned member attachable to the rear of said body portion, a charge retaining ring, said ring being mounted between said body portion and said finned member, an electrical squib mounted adjacent said charge, a pair of electrical contact surfaces on the periphery of the rocket projectile, at least one of said contact surfaces being insulated with respect to the rocket projectile, and electrical conductors connecting each of said contact surfaces to said electrical squib.

3. In a rocket projectile, a hollow body por-

tion, a self-contained propulsion charge insertable in said body portion, means for retaining said charge within said body portion, an electrical squib mounted adjacent said charge, a contact ring mounted around the periphery of the rocket projectile and insulated therefrom, a first squib wire connecting to said contact ring and a second squib wire connecting to the periphery of the rocket projectile.

4. In a rocket projectile, a hollow body portion, a self-contained propulsion charge insertable in said body portion, said charge comprising a substantially cylindrical bundle of powder sticks, said sticks being secured together to form an axial cavity extending thru said bundle, means for retaining said charge within said body portion, an electrical squib mounted within said axial cavity of said powder charge, a pair of electrical contact surfaces on the periphery of the rocket projectile, at least one of said contact surfaces being insulated with respect to the rocket projectile, and electrical conductors connecting each of said contact surfaces to said electrical squib.
